UNITED STATES PATENT OFFICE.

MICHAEL A. DROITCOUR, OF EDGEWOOD, RHODE ISLAND.

SHEET-DELIVERY APPARATUS.

Application filed January 5, 1922, Serial No. 527,125. Renewed September 14, 1927.

This invention is a novel mechanism for delivering and piling sheets of papers. It is especially designed for use in connection with printing presses but can be used in connection with other machines, such as ruling machines, perforators, scoring, bronzing, and numbering machines; and is adapted to handle sheets one at a time, or several at a time.

The principal objects of the invention are to produce a self contained delivery unit; to provide a reciprocable angularly disposed sheet carrier moving in a horizontal and in a vertical direction; to operate the reciprocating carrier by endless belts or chains; to provide novel means for causing these chains to reciprocate so that when moving in one direction a sheet will be forwarded over the pile and when moving in the opposite direction the sheet will be dropped upon the pile; to provide novel means for preventing overrunning of the sheets while being carried out over the pile; to provide a reciprocating carrier whose motion will be uniform for the greater part of its travel in both directions, and have a true crank reverse at each end of its travel; and to provide a mechanism which can be driven in exact unison with the operation of the press or other machine whose product it is receiving but which is practically entirely independent of such machine except for the single timing and driving connection. Other minor objects and advantages of the invention will be hereinafter set forth.

In the accompanying drawings I have illustrated one practical embodiment of the invention and will describe it with reference to said drawings to enable others to adopt and use the same, but I do not consider the invention restricted or limited to the particular construction of apparatus shown in said drawings and therefore refer to the claims for summaries of the essentials of the invention and the novel combinations of parts and the novel features of construction for all of which protection is desired.

In said drawings:

Fig. 1 is a rear end elevation of the complete delivery unit or machine.

Fig. 2 is a side elevation thereof.

Fig. 3 is an enlarged detail section of the device for operating the sheet detaining stops.

Fig. 4 is a detailed sectional view showing part of the carrier showing the sheet stops.

Fig. 5 is an enlarged view showing the re-

ciprocating carrier and its operating devices, and the sheet controlling devices coacting therewith.

Figs. 6 and 7 are diagrammatical views 60 illustrating the operation of the carrier in delivering the sheet.

Fig. 8 is a detail view of the scotch-yoke devices for operating the carrier.

The operative parts of the device, may be 65 mounted in any suitable frame or support. As shown the frame has four corner uprights 1, which are suitably connected together to form a substantially rigid frame.

Attached to the front or inner end of the 70 said frame (adjacent one end of the press, or other machine, with which the delivery unit is to be used) is a bearing 2^a for a driving shaft 2, which may be operatively connected with or geared to the driving mechanism or driving shaft of the said press so as to have a proper and accurately timed rotation relative the operative mechanism of said press. Shaft 2 preferably is geared so as to make one full revolution for each cycle of 80 operations of the press or machine.

On the end of shaft 2, in the frame 1, is a sprocket 2^a; and above the sprocket 2^a is a similar sprocket 2^b mounted on a stud 2^c suitably mounted on the frame 1; and around these sprockets 2^a, 2^b runs an endless sprocket chain 2^e.

Suitably connected to this sprocket chain and traveling therewith is a crank pin 3 which is operatively engaged with a block 90 3^a slidably mounted in a yoke casting 3^b attached to a bar 3^c which lies beside and at right angles to the parallel runs of the chain 2^e and is connected at its ends to opposite parallel endless chains 4. The chain 2^e, pin 95 3, block 3^a and yoke casting 3^b together form a scotch yoke movement whereby the bar 3^c is raised and lowered vertically during each complete orbital movement of the pin 3 throughout the length of the chain 2^e thereby imparting a reciprocating movement to the chains 4.

The chains 4 (see Fig. 5) run over sprockets 4^a on a shaft 4^c (suitably journaled or supported in bearings on the frame adjacent 105 the inner pair of uprights 1) then up over sprockets 4^b mounted on studs or shafts 4^c near the upper ends of the said uprights. Sprockets 4^a are in vertical alinement with and above the sprockets 4^b so that the runs 110 of the chains 4 between the sprockets 4^a and 4^b are in a plane parallel with the plane of

the chain 2^c. From the sprockets 4^d the chains 4 pass horizontally outward to and over sprockets 4^f mounted on studs 4^g attached to the frame adjacent the outer pair 5 of uprights 1. The sprockets 4^f are in alignment with and preferably in the same horizontal plane as sprockets 4^d so that the upper portions of the runs of the chains 4 are horizontal and practically at an angle of 90° 10 to the vertical portions of the runs of said chains 4. From sprockets 4^f the chains 4 pass back toward sprockets 4^d to and over sprockets 4^b mounted on studs 4ⁱ suitably supported on brackets attached to the inner 15 uprights 1; and from the sprockets 4^b the chains 4 pass vertically downward to the sprockets 4^b, from whence they started. The opposite chains 4 are thus parallel throughout and extend vertically for part of their 20 length, between the sprockets 4^b, 4^h; and then extend horizontally, for the remainder of their length, between the sprockets 4^a, 4^h, and 4^f.

The bar 3^b being fast to the vertical portions 25 of the runs of the chains 4, said chains will be caused to reciprocate by and with the movement of the yoke 3^s, and will therefore have a uniform movement, corresponding to that of the yoke, while the yoke is transversing 30 the distance between the shafts 2 and 2° on each stroke; and said chains will be given a true crank reverse, at the ends of the uniform movement of the yoke, while pin 3 is passing around sprocket 2^a or 2^b.

Mounted upon and carried by and between the parallel chains 4 are two tape rollers 5 and 5^a. Any suitable bearings for the journals of the rollers 5, 5^a, may be provided and attached to the chains 4 in any well 40 known manner. The roller 5 is mounted in bearings attached to the vertical portions of the runs of the chains 4 adjacent to but above the yoke 3^b; and the roller 5^a is mounted in bearings attached to the horizontal portion 45 of the runs of the chains 4, at such a distance from the roller 3 that when roller 5 is in its uppermost position, (adjacent sprockets 4^d) the roller 5^a will be in its outermost position (adjacent sprockets 4^f); and when the roller 5 is in its lowermost position, roller 5^a will be in its innermost position, (adjacent sprocket 4^b).

A roller 5^b is mounted in suitable bearings 55 on frame adjacent the inner uprights 1, and lies above the roller 5, and above but adjacent the inner side of the sprockets 4^b. Parallel with and beside the roller 5^b is a similar roller 5^c journaled in suitable bearings in the frame adjacent the inner uprights 1. 60 The said rollers 5^a, 5^b, 5^c carry a set of endless tapes 5^e. These tapes, starting from the roller 5, run upwardly over roller 5^b, then horizontally to and over the roller 5^a, then back to and over the roller 5^c, and then down 65 the roller 5.

The set of tapes 5^e are reciprocated back and forth by, with, and as, the chains 4. The upper horizontal portions of the tapes 5^e lengthen or shorten as the roller 5^a moves toward or away from the roller 5^b; and the 7^b vertical portions of the tapes 5^e lengthen or shorten as the roller 5 moves toward or away from the roller 5^b. The vertical loops of the tapes 5^e lengthening as and in accordance with the shortening of the horizontal 75 loops thereof, and vice versa.

Mounted on the ends of the rollers 5, 5^a, 5^b, and 5^c are sprockets 5^t, 5^t, 5^s, 5^h over which runs an endless sprocket chain 5^t (see Fig. 5). The upper run of this chain 5^t is 80 engaged by a pawl 5^j mounted on the frame (see Fig. 5). This pawl does not interfere with the linear movement of the chain 5^t when the roller 5^a is moving outwardly toward the sprocket 4^f, but when the roller 5^a starts inward toward the sprocket 5^c, said pawl 5^j prevents inward movement of the upper run of the chain 5^t, and consequently the rotation of roller 5^b is prevented, but its travel is not interfered with, with the result 85 that the roller 5^a is rotated by the movement of the portions of the tapes 5^e and chain 5^t which pass from the upper runs or loops thereof to the lower runs or loops to supply the demand of the loop taken up by the 90 roller 5. Any other suitable means may be used to arrest the movement of the tapes to drop the sheet as above described.

When the roller 5^a moves outwardly away from the roller 5^b the pawl 5^j does not affect 100 the chain 5^t and there will be a uniform movement of both the upper and lower portions of the tapes 5^e and chain 5^t, and consequently there will be no rotation of the rollers 5, 5^a, and the sheet S will be simply 105 carried out on the upper portions of the tapes 5^e as indicated in Fig. 6. When the roller 5^a starts inward the upper runs of tapes 5^e will be held stationary, as described, while the roller 5^a is rotated by the movement of the intermediate lower portion of the tapes from roller 5^a back to and around roller 5; the upper loop of the tapes 5^e simply dropping away or withdrawing, from 110 beneath the sheet S and depositing it upon the pile board 6, as indicated in Fig. 7. The sheets are received upon the upper horizontal runs of the tapes 5^e and carried thereby out over a pile board 6 (Fig. 6) and dropped upon the pile when the upper run of the 115 tapes recedes (Fig. 7).

The pile is supported upon a board 6 shown as suspended by chains 6^a from sheaves 6^b on shafts 6^c, arranged at opposite sides of the frame, and journaled in suitable 120 bearings attached to the frame adjacent the upper ends of the uprights 1. On shafts 6^c are worm gears 6^d (Fig. 2) meshing with worms 6^e on a shaft 7 journaled in suitable brackets on the uprights 1. The shaft 7 125

may be slowly rotated by means of a sprocket 7^a, on shaft 7, driven by a chain 7^b from a sprocket 7^c loosely mounted on a short shaft 7^d mounted in suitable bearings 5 on the base of the feeder frame. The sprocket 7^c is adapted to be engaged by a suitable clutch member indicated at 7^e, which may be loosely splined on shaft 7^d, and which can be moved into or out of engagement with the sprocket 7^c in the usual manner, or by any suitable means to engage or disengage the sprocket 7^c from this shaft 7^d.

Shaft 7^d carries a bevel gear 7^f meshing with a bevel 7^g on a shaft 7^h driven by any 15 suitable means. When the delivery unit is used in connection with a printing press the shaft 7^h is preferably connected with and driven by the feeder mechanism (not shown) by which the sheets are supplied 20 from a pile and are fed to the press (not shown) in the well known manner so that the delivery board 6 lowers as the feed board raises and the pile of sheets thereon is reduced.

25 When it is desired to raise or lower the board 6 quickly, clutch 7^e can be disengaged from the sprocket 7^c and a crank handle 7^m applied to the shaft 7 to turn it by hand. This crank handle could be applied to a stud shaft 7^m mounted in a bearing 7^s attached to the frame and carrying a sprocket 7° connected by a sprocket chain 7^p to a small sprocket 7^r on shaft 7. By the said means 30 the pile board 6 may be raised or lowered to 35 adjust the pile or the board prior to the automatic operation of the machine.

A rod 9 is mounted on the chains 4 adjacent the roller 5^a and parallel with but above said roller. This rod carries stop finger 9^a. 40 On one end of rod 9 is an arm 9^b (see Fig. 3) which has a recess 9^c in which is mounted an expansion spring 9^d which may have a friction plate 9^e of any suitable material on its outer end adapted to engage a bar 10 supported on 45 brackets 10^a attached to the frame (see Figs. 3 and 4). A friction plate 9^f, of any suitable material, may be attached to the outer side of arm 9^b and slidably engage the outer side of the bar 10 opposite the plate 9^e.

50 The sheet stops are moved backward and forward with the roller 5^a; and on the outward stroke the friction devices 9^e, 9^f engaging bar 10 cause rod 9 to rock and move the stop fingers 9^a into position to prevent the sheet S over running roller 5^a. On the return stroke the friction devices cause the shaft to rock so as to raise the stop fingers 9^a (see Fig. 4) so they will not interfere with the dropping of the sheet over the roller.

55 A rod 11 is mounted on the inner end of the frame adjacent and above the roller 5^b and on this rod are mounted adjustable guide fingers 11^a by which the sheets brought forward by the tapes 8 are properly directed 60 to and laid upon the upper run of tapes 5^e.

The delivery unit as shown may be used in connection with an ordinary sheet printing press and the shaft 2 driven by suitable gearing from the driving mechanism of the press, so that the gear 2° has an exact synchronous timed relation to the press, and is rotated once for each cycle of operations of the press (or other machine for operating upon sheets). 70

The sheets are fed to the press (or other machine for operating upon sheets) preferably by an automatic feeder (not shown) and after being printed are transferred from the press (or other machine for operating upon sheets) to the delivery unit by delivery 75 tapes 8 running from the press to a roller 8^a mounted in the delivery frame adjacent roller 5^b, as indicated in Figs. 2 and 5, so that tapes 8 will discharge the sheets directly over roller 5^b onto the upper horizontal 80 portions or runs of the tapes 5ⁱ (see Fig. 5). Tapes 8, and 5ⁱ all travel at substantially the same linear speed, so that the sheets are successively brought from the press and passed out onto the upper runs of the tapes 5ⁱ, as 85 roller 5^a moves outwardly, away from roller 5^b, and the sheet is carried thereby out over the pile board 6 (see Fig. 6); and as the roller 5^a moves inward, toward roller 5^b, the upper runs of the tapes 5ⁱ move from 90 beneath the sheet and drop it upon the board 6 (see Fig. 7) as above described.

The board 6 is preferably lowered automatically, as the pile of sheets increases in height.

While I have hereinbefore referred to 100 chains it is obvious that any suitable flexible means might be used in lieu of the chains. The delivery unit is adapted for use not only in connection with printing presses but also with many other machines for operating 105 upon sheets; and also it is adapted to handle single wide sheets, or a plurality of narrow sheets side by side, or a plurality of sheets superposed one upon the other. I also do not consider the invention restricted to the 110 specific form of apparatus shown, as it is capable of embodiment in various structural forms within the scope of the invention.

I claim:

1. In combination a pair of endless carriers, a yoke connected with the carriers, a pin slidably connected with said yoke, an endless chain carrying said pin, and means for driving the endless chain and thereby imparting reciprocatory movement to the 115 yoke and carriers, substantially as described.

2. In combination an endless carrier, a yoke connected with the carrier, a pin slidably connected with said yoke, an endless chain carrying said pin, and means for driving the endless chain and thereby imparting reciprocatory movement to the yoke and carrier, substantially as described.

3. In combination a pair of endless chains 120 extending in an angular path and having a 125

vertically extending portion and a horizontally extending portion; guide sprockets for said chains located at the junction of said portions; rollers mounted on said chains and carrying a set of endless tapes, means for imparting reciprocatory movements to said chains to bodily reciprocate the said tapes; a yoke connected with said chains, a pin slidably connected with said yoke, an endless chain carrying said pin, and means for driving the endless chain and thereby imparting reciprocatory movement to the yoke.

4. In apparatus as set forth, a pair of endless chains extending in an angular path and having a vertically extending portion and a horizontally extending portion; guide sprockets for said chains located at the junction of said portions; a pair of endless tapes, rollers mounted on said chains by which the said tapes are moved; and means for imparting reciprocatory motion to the said tapes.

5. In apparatus as set forth in claim 4, a yoke connected with the chains, a pin slidably connected with said yoke, an endless chain carrying said pin, and means for driving the endless chain and thereby imparting reciprocatory movement to the yoke and chains connected therewith, substantially as described.

6. In apparatus of the character specified, a tape roller moving in a vertical direction; a second tape roller moving in a horizontal direction; and intermediate tape guide rollers located above the vertically movable roller and to one side of the horizontally movable roller; endless tapes running from one movable roller to the other and guided by the intermediate rollers whereby the tapes are bent so as to have a vertical loop and a horizontal loop; and means for reciprocating the entire set of tapes endwise to alternately lengthen and shorten the respective portions.

45 7. In apparatus as set forth in claim 6, a pair of endless chains beside the path of the endless tapes and having vertically extending portions and horizontally extending portions; guide sprockets for said chains located at the junction of said portions; movable tape rollers being mounted on said chains; and means for imparting oscillatory motion to said chains to bodily reciprocate the said tapes.

55 8. In apparatus as set forth in claim 6 a pair of endless chains beside the path of the endless tapes and having vertically extending portions and horizontally extending portions; guide sprockets for said chains located at the junction of said portions; the movable tape rollers being mounted on said chains; a yoke connected with said chains, a pin slidably connected with said yoke, and an endless chain carrying said pin, substantially as described.

9. In apparatus as set forth in claim 6, endless chains having vertically extending portions and horizontally extending portions; guide sprockets for said chains at the junction of said portions, said tapes being carried by said chains; and means to impart bodily reciprocatory motion to the said chains.

10. In apparatus as set forth in claim 6, a pair of endless chains beside the path of the endless tapes and having vertically extending portions and horizontally extending portions, guide sprockets for said chains located at the junction of said portions; the movable tape rollers being mounted on said chains; a yoke connected with the tape carriers, a pin slidably connected with said yoke, an endless chain carrying said pin, and means for driving the endless chain and thereby imparting reciprocatory movement to the yoke and chains, substantially as described.

11. In apparatus of the character specified, a reciprocating sheet carrier, a rod moving with the carrier, stop fingers on the rod, a bar beside the carrier, an arm on the rod, and friction means carried by said arm engaging said bar whereby the rod is rocked in one direction during one movement of the carrier to hold the fingers in sheet engaging position, and is rocked in the opposite direction on the opposite movement of the carrier to hold the stop fingers out of sheet engaging position.

12. In sheet delivery apparatus, a reciprocating sheet carrier movable in an angular path, an endless drive belt, and a crank connection between said belt and the carrier for reciprocating the carrier.

13. In combination with a reciprocating carrier as set forth in claim 12, a rod mounted on the carrier, stop fingers mounted on said rod and means for oscillating the rod to cause the fingers to arrest the sheet on one movement of the carrier and to move out of the way of the sheets on the reverse movement of the carrier.

14. In sheet delivery apparatus, a reciprocating sheet carrier having one portion extending vertically and another portion extending horizontally, flexible means operatively connected with the respective portions of the carrier, an endless drive belt, and a crank connection between said belt and said means for reciprocating the carrier.

15. In combination with mechanism as set forth in claim 14, a reciprocating sheet carrier, a rod, stop fingers on the rod, an arm on the rod, and friction means carried by said arm whereby the rod is rocked in one direction during one movement thereof to hold the fingers in sheet engaging position, and rocked in the opposite direction on the return movement thereof to hold the stop fingers out of sheet engaging position.

16. In combination a reciprocating sheet carrier extending in an angular path, and means for guiding said carrier at the bend of its path, flexible means operatively connected with the carrier; an endless drive belt, and a crank connection between said belt and said means for reciprocating the carrier.

17. In combination with mechanism as set forth in claim 16, a rod, stop fingers on the rod, an arm on the rod, a bar and friction devices carried by said arm to engage said bar, whereby the rod is rocked in one direction during one movement thereof to hold the fingers in sheet engaging position, and is rocked in the opposite direction on the opposite movement thereof to hold the stop fingers out of sheet engaging position.

18. In combination a sheet carrier extending in an angular path, means for guiding said carrier at the bend of the path; flexible means operatively connected with the carrier; an endless drive belt; and a scotch yoke driving connection between said belt and said means for imparting a bodily reciprocatory motion to the said carrier.

19. In sheet delivery apparatus, a reciprocating sheet carrier moving in an angular path; means for guiding the carrier at the bend of its path; flexible means operatively connected with the carrier; an endless drive belt, and a crank connection between said belt and said means for reciprocating the carrier.

20. In sheet delivery apparatus, a reciprocating sheet carrier having one portion extending vertically and another portion extending horizontally; means for guiding the carrier at the bend of its path; flexible means operatively connected with the respective portions of the carrier; an endless drive belt, and a crank connection between said belt and said means for reciprocating the carrier.

21. In combination a sheet carrier extending in an angular path, means for guiding said carrier at the bend of the path; endless tapes carried by said carrier; flexible means operatively connected with the carrier; an

endless drive belt; and a scotch yoke driving connection between said belt and said means.

22. In combination endless carriers extending in an angular path, guides for said carriers at the bend of the path; endless tapes carried by said carriers; flexible means operatively connected with said carriers; an endless drive belt; and a crank connection between said belt and said means for reciprocating the carrier to impart a bodily reciprocatory motion to the said tapes, substantially as described.

23. In combination a pair of endless carriers moving in an angular path and having a vertically extending portion and a horizontally extending portion; rollers mounted on said carriers; endless tapes running on said rollers and extending in an angular path parallel with that of the carriers; a yoke connected with the carriers, a pin slidably connected with said yoke, an endless chain carrying said pin, and means for driving the endless chain and thereby imparting reciprocatory movement to the yoke and carrier, substantially as described.

24. In apparatus of the character specified, a tape roller moving in a vertical direction, a second tape roller moving in a horizontal direction, intermediate tape guides located above the vertically movable roller and to one side of the horizontally movable roller; endless tapes running from one movable roller to the other and guided by the intermediate guides, whereby the tapes are bent so as to have a vertical loop and a horizontal loop; endless chains extending in an angular path and having a vertically extending portion and a horizontally extending portion; guide sprockets for said chains at the junction of said portions, said tapes being carried by said chains, and means for imparting an oscillatory motion to said chains to impart bodily reciprocatory motion to the said tapes.

In testimony that I claim the foregoing as my own I affix my signature.

MICHAEL A. DROITCOUR.
